Primary Examiner — Dameon E Levi*Assistant Examiner* — Jennifer F Hu(74) *Attorney, Agent, or Firm* — Clause Eight; Michael Catania(57) **ABSTRACT**

A 5G broadband antenna is disclosed herein. The 5G broadband antenna comprises a first antenna element and a second antenna element. Each of the first antenna element and the second antenna element has a main branch with a slot therein. The antenna apparatus covers a first frequency band of 617-960 MegaHertz, a second frequency band of 1.4-1.6 GigaHertz (GHZ), a third frequency band of 1.71-2.7 GHz, a fourth frequency band of 3.3 to 4.2 GHz, and a fifth frequency band of 4.3 to 6.0 GHz.

5G BROADBAND ANTENNA**CROSS REFERENCE TO RELATED APPLICATION**

The Present Application is a continuation-in-part application of U.S. patent application Ser. No. 16/258,611, filed on Jan. 27, 2019, which claims priority to U.S. Patent Application No. 62/793,871, filed on Jan. 17, 2019, each of which is hereby incorporated by reference in its entirety.

STATEMENT REGARDING FEDERALLY SPONSORED RESEARCH OR DEVELOPMENT

Not Applicable

BACKGROUND OF THE INVENTION**Field of the Invention**

This invention relates to 5G broadband antennas.

Description of the Related Art

The prior art discusses various broadband antennas.

Jeng, U.S. Patent Publication Number 20120218164 for a Compact Size Antenna Operating In LTE Frequency Bands, discloses an antenna that meets the 2G/3G/LTE communications systems.

Islam, U.S. Patent Publication Number 20130009836 for a Multi-Band Antenna And Methods For Long Term Evolution Wireless System discloses an antenna with a first structure operable in a lower frequency long term evolution application band and a second structure operable in a second frequency band.

Wong et al, U.S. Patent Publication Number 20130016013 for a Mobile Communication Device And Antenna Device, discloses a mobile communication device operating in LTE and WLAN bands.

Current wireless communication devices such as cellular phone, laptop, tablet computer etc. have an increasing demand for multi-band, high gain, high efficiency and compact size LTE antennas. However, in most cases the design of multi-band LTE antenna is very difficult since it is very hard to get enough bandwidth with good return loss for each frequency band.

General definitions for terms utilized in the pertinent art are set forth below.

BLUETOOTH technology is a standard short range radio link that operates in the unlicensed 2.4 gigahertz band.

Code Division Multiple Access (“CDMA”) is a spread spectrum communication system used in second generation and third generation cellular networks, and is described in U.S. Pat. No. 4,901,307.

GSM, Global System for Mobile Communications is a second generation digital cellular network.

The Universal Mobile Telecommunications System (“UMTS”) is a wireless standard.

Long Term Evolution (“LTE”) is a standard for wireless communication of high-speed data for mobile phones and data terminals and is based on the GSM/EDGE and UMTS/HSPA communication network technologies.

LTE Frequency Bands include 698-798 MHz (Band 12, 13, 14, 17); 791-960 MHz (Band 5, 6, 8, 18, 19, 20); 1710-2170 MHz (Band 1, 2, 3, 4, 9, 10, 23, 25, 33, 34, 35, 36, 37, 39); 1427-1660.5 MH (Band 11, 21, 24); 2300-2700

MHz (Band 7, 38, 40, 41); 3400-3800 MHz (Band 22, 42, 43); 5150-5925 MHz (Band 46, 47).

Antenna impedance and the quality of the impedance match are most commonly characterized by either return loss or Voltage Standing Wave Ratio.

Surface Mount Technology (“SMT”) is a process for manufacturing electronic circuits wherein the components are mounted or placed directly onto a surface of a printed circuit board (“PCB”).

10 The APPLE IPHONE® XS LTE bands include 1, 2, 3, 4, 5, 7, 8, 12, 13, 14, 17, 18, 19, 20, 25, 26, 29, 30, 32, 34, 38, 39, 40, 41, 46, 66, 71, and the frequency range covers from 617 MHz up to 5925 MHz.

15 The SAMSUNG GALAXY® S8 LTE Bands include 1, 2, 3, 4, 5, 7, 8, 12, 13, 17, 18, 19, 20, 25, 26, 28, 29, 30, 32, 40, 41, 46, 66, and the frequency range covers from 699 MHz up to 2690 MHz.

17 LG G7 ThinQ LTE bands include 1, 2, 3, 4, 5, 7, 8, 12, 13, 17, 20, 25, 26, 30, 40, 41, 66, 71, and the frequency range 20 covers from 617 MHz up to 2690 MHz.

For wireless communication devices applications, there are generally three challenging requirements for embedded antenna: good performance, compact size and low cost. What is needed is an antenna that can meet the needs of the 25 5G broadband mobile device market.

BRIEF SUMMARY OF THE INVENTION

One aspect of the present invention is 5G broadband 30 antenna apparatus. The antenna apparatus comprises a first antenna element and a second antenna element and base. The first antenna element comprises first body with a first long branch, a first middle section having a first slot therein, and a first short branch shorter in length than the long branch. The second antenna element comprises a second body with a second long branch, a second middle section having a second slot therein, and a second short branch shorter in length than the long branch. The antenna apparatus covers a first frequency band of 617-960 MegaHertz, 35 a second frequency band of 1.4-1.6 GigaHertz (GHz), a third frequency band of 1.71-2.7 GHz, a fourth frequency band of 3.3 to 4.2 GHz, and a fifth frequency band of 4.3-6.0 GHz. The antenna apparatus has a length ranging from 140 millimeters (mm) to 165 mm, and a width ranging from 20 45 mm to 35 mm.

Having briefly described the present invention, the above and further objects, features and advantages thereof will be recognized by those skilled in the pertinent art from the following detailed description of the invention when taken in conjunction with the accompanying drawings.

DETAILED DESCRIPTION OF THE INVENTION

An antenna apparatus **20** is shown in FIGS. 1-2. The antenna apparatus **20** preferably comprises a first antenna element **21** and a second antenna element **22** and base **50**. The first antenna element **21** comprises first body with a first main branch **23** having a first slot **40a** therein, a first mid-branch **27**, and a first lower branch **25** shorter in length than the first mid-branch **27**. The second antenna element **22** comprises a second body with a second main branch **24** having a second slot **40b** therein, a second mid-branch **28**, and a second lower branch **26** shorter in length than the second mid-branch **28**. The first main branch **23** has a first vertical section **21a** and the second main branch **24** has a second vertical section **22a**.

The antenna apparatus **20** covers a first frequency band of 617-960 MegaHertz, a second frequency band of 1.4-1.6 GigaHertz (GHZ), a third frequency band of 1.71-2.7 GHz, a fourth frequency band of 3.3 to 4.2 GHz, and a fifth frequency band of 4.3 to 6.0 GHz. The antenna apparatus **20** has a length, L_1 , preferably ranging from 150 millimeters (mm) to 175 mm, and most preferably 162 mm. The antenna apparatus **20** has a width, W_1 , preferably ranging from 25 mm to 40 mm, and most preferably 33 mm. The antenna apparatus **20** also has a pad **31** for a cable inner conductor soldering which is approximately 2×1.5 mm and is located on the first antenna element **21**, and a pad **32** for a cable outer conductor soldering which is approximately 3×3 mm and is located on the second antenna element **22**.

Operating Bands: 617 MHz to 960 MHz; 1.4 GHz to 1.7 GHz; 1.71 GHz to 2.7 GHz; and 3.3 GHz to 4.2 GHz. The Return Loss Spec: -6 dB across band.

A 5G broadband antenna has been designed to meet the market requirement;

The 5G broadband antenna covers a first frequency band of 617-960 MegaHertz, a second frequency band of 1.4-1.6 GigaHertz (GHZ), a third frequency band of 1.71-2.7 GHz, a fourth frequency band of 3.3 to 4.2 GHz, and a fifth frequency band of 4.3 to 6.0 GHz.

A dipole-type 5G broadband cable-fed antenna has been developed to meet market requirement, and its radiation pattern is omni-directional in a plane perpendicular to antenna length;

Return loss: Better than -6 dB across all operation bands (617-960 MHz, 1.4-1.6 GHz, 1.71-2.7 GHz, 3.3-4.2 GHz);

High average efficiency for 617-960 MHz band obtained: 73%.

Average efficiency for 1.4-1.6 GHz band: 68%.

Average efficiency for 1.71-2.7 GHz band: 76%.

Average efficiency for 3.3-4.2 GHz band: 78%.

Average efficiency for 4.3-6.0 GHz band: 70%.

Peak gain for 617-960 MHz band: -0.9-1.9 dBi.

The length of the antenna is 5 mm shorter than an existing wideband LTE antenna N700L series from Airgain Incorporated, and overall performance is better than the N700L series.

5 Operation bands: 617-960 MegaHertz, a second frequency band of 1.4-1.6 GigaHertz (GHZ), a third frequency band of 1.71-2.7 GHz, a fourth frequency band of 3.3 to 4.2 GHz, and a fifth frequency band of 4.3 to 6.0 GHz.

10 The total antenna length (162 mm) creates lowest frequency band (base mode f_0 (617-960 MHz) and its high order modes (2^*f_0 , 3^*f_0 , . . . etc.).

15 The first main branch **23** and the second main branch **24** are two “fat” sections with slots **40a** and **40b** used to increase the low band bandwidth to cover 617-960 Mhz.

15 The first mid-branch **27** and the second mid-branch **28** cover the wide bandwidth for the middle bands ranging 1.4 GHz to 1.6 GHz and 1.71 GHz to 2.7 GHz. The first mid-branch **27** and the second mid-branch **28** combine with 20 the high order modes of the antenna base mode to get wide bandwidth for the middle bands (1.4 GHz to 1.6 GHz and 1.71 GHz to 2.7 GHz).

25 The first lower branch **25** and the second lower branch **26** cover the wide bandwidth for the high bands ranging 3.3 GHz to 4.2 GHz and 4.3 GHz to 6.0 GHz. These two shorter branches **25** and **26** are used to increase the bandwidth of the high bands. These two shorter branches **25** and **26** combine with the high order modes of the antenna base mode to get wide bandwidth for the high bands (3.3 GHz to 4.2 GHz and 4.3 GHz to 6.0 GHz).

30 This Dipole-type broadband antenna covers the frequency bands of 617-960 MHz, 1.4-1.7 GHz, 1.71-2.7 GHz, 3.3-4.2 GHz and 4.3 GHz to 6.0 GHz.

35 The total antenna length is determined by electrical small antenna rule and the free space wavelength of the lowest frequency 617 MHz (free space wavelength of 617 MHz: 486.2 mm); This length will create lowest frequency band (base mode f_0) and also high order modes (2^*f_0 , 3^*f_0 , . . . etc.).

40 The most difficult design of this antenna is that it is very hard to get wide bandwidth to cover a low band of 617-960 MHz. To get a wide bandwidth for a low band, two “fat” sections (the first main branch **23** and the second main branch **24**) with slots **40a** and **40b**, were added on the main antenna body which is able to increase the low band bandwidth significantly.

45 The antenna apparatus **20** has a return loss spec of -6 dB across the band.

50 Thill, U.S. patent Ser. No. 10/109,918 for a Multi-Element Antenna For Multiple bands Of Operation And Method Therefor, which is hereby incorporated by reference in its entirety.

55 The antenna preferably operates on an 802.11 communication protocol. Most preferably, the second antenna element **43** operates on an 802.11n communication protocol. Alternatively, the antenna operates on an 802.11b communication protocol. Alternatively, the antenna operates on an 802.11g communication protocol. Alternatively, the antenna operates on an 802.11a communication protocol. Alternatively, the antenna operates on an 802.11ac communication protocol.

60 From the foregoing it is believed that those skilled in the pertinent art will recognize the meritorious advancement of this invention and will readily understand that while the present invention has been described in association with a preferred embodiment thereof, and other embodiments illustrated in the accompanying drawings, numerous changes modification and substitutions of equivalents may be made therein without departing from the spirit and scope of this

invention which is intended to be unlimited by the foregoing except as may appear in the following appended claim. Therefore, the embodiments of the invention in which an exclusive property or privilege is claimed are defined in the following appended claims.

We claim as our invention:

1. A 5G broadband antenna apparatus, the antenna apparatus comprising:

a first antenna element comprising a first body with a first main branch having a first internal slot therein, a first mid-branch, and a first lower branch shorter in length than the first mid-branch and the first mid-branch between the first main branch and the first lower branch;

a second antenna element comprising a second body with a second main branch having a second internal slot therein, a second mid-branch, and a second lower branch shorter in length than the second mid-branch and the second mid-branch between the second main branch and the second lower branch;

wherein the antenna apparatus covers a first frequency band of 617-960 MegaHertz, a second frequency band of 1.4-1.6 GigaHertz (GHz), a third frequency band of 1.71-2.7 GHz, a fourth frequency band of 3.3 to 4.2 GHz, and a fifth frequency band of 4.3 to 6.0 GHz;

wherein the first lower branch and the second lower branch cover the high band bandwidth ranging 3.3 to 4.2 GHz and the high band bandwidth ranging 4.3 to 6.0 GHz.

2. The antenna apparatus according to claim 1 further comprising a base, wherein the first antenna element and the second antenna element are disposed on a surface of the base.

3. The antenna apparatus according to claim 2 further comprising a feed coaxial cable with an inner conductor connected to a feed point on the first antenna element and with an outer conductor connected to a grounding point on the second antenna element.

4. The antenna apparatus according to claim 1 wherein the antenna apparatus has a length ranging from 150 millimeters (mm) to 175 mm, and a width ranging from 25 mm to 40 mm.

5. The antenna apparatus according to claim 2 wherein the base is a PCB.

6. A 5G broadband antenna apparatus, the antenna apparatus comprising:

a base;

a first antenna element comprising a first body with a first main branch having a first internal slot therein, a first mid-branch, and a first lower branch shorter in length than the first mid-branch;

a second antenna element comprising a second body with a second main branch having a second internal slot therein, a second mid-branch, and a second lower branch shorter in length than the second mid-branch; wherein the antenna apparatus covers a first frequency band of 617-960 MegaHertz, a second frequency band of 1.4-1.6 GigaHertz (GHz), a third frequency band of 1.71-2.7 GHz, a fourth frequency band of 3.3 to 4.2 GHz, and a fifth frequency band of 4.3 to 6.0 GHz; wherein the first lower branch and the second lower branch cover the high band bandwidth ranging 3.3 to 4.2 GHz and the high band bandwidth ranging 4.3 to 6.0 GHz.

7. The antenna apparatus according to claim 6 wherein the first main branch and the second main branch cover the low band bandwidth ranging 617 MHz to 960 MHz.

8. The antenna apparatus according to claim 6 wherein the antenna apparatus has a length ranging from 150 millimeters (mm) to 175 mm, and a width ranging from 25 mm to 40 mm.

9. The antenna apparatus according to claim 6 further comprising a feed coaxial cable with an inner conductor connected to a feed point on the first antenna element and with an outer conductor connected to a grounding point on the second antenna element.

10. The antenna apparatus according to claim 6 wherein the first main branch has a first vertical section and the second main branch has a second vertical section.

11. The antenna apparatus according to claim 6 wherein the first mid-branch and the second mid-branch cover the wide bandwidth for the middle bands ranging 1.4 GHz to 1.6 GHz and 1.71 GHz to 2.7 GHz.
